UNITED STATES PATENT OFFICE.

EDWIN C. LILLIE, OF DENVER, COLORADO.

PROCESS OF PROMOTING COMBUSTION.

1,312,916.

Specification of Letters Patent.

Patented Aug. 12, 1919.

Application filed May 16, 1916. Serial No. 97,828.

To all whom it may concern:

Be it known that I, EDWIN C. LILLIE, a citizen of the United States, and a resident of Denver, in the county of Denver and 5 State of Colorado, have invented a certain new and useful Process of Promoting Combustion, of which the following is a full, clear, and exact description.

My invention is an improvement in methods of burning fuel and its objects are the utilization of all the heat units in the fuel through complete combustion of its oxidizable constituents, including the gases, and the consequent elimination of smoke. While 10 its principles are of general applicability my invention contemplates more particularly the provision of a process by which fine, slack or other low grade coal may be burned efficiently and without smoke under 15 steam or hot water heating boilers; and it is in connection with a couple of different types of installations for this purpose that I have illustrated and shall describe it though I do not wish to be considered as 20 limited to the application selected or to the type of installation illustrated further than the appended claims may indicate.

I have discovered that smokeless and complete combustion of coal may be had (even 25 in connection with boilers for domestic heating where attention can be given the fire only at long intervals) provided that the volatile hydrocarbons, free carbon, and carbon monoxide liberated or generated during 30 the process of burning shall be expelled slowly and directly into and thoroughly and intimately mixed with a flame resulting from the combustion of the fixed carbon content of the fuel and in the presence of 35 an excess of oxygen. As an aid in attaining these conditions I maintain a relative deep body of fuel, only the lower portion of which is at the ignition temperature. Ignition of the entire column of fuel may be prevented 40 either by the nature of the fuel bed, it being so deep and fine that gases can not pass up through it under the draft conditions maintained, or by inclosing the upper portion of the fuel body in a closed chamber on which 45 50 no draft is maintained, the distillates and products of combustion finding an exit only below the lower edges of said chamber. As

a further aid in attaining the proper conditions I limit the breadth of the fuel bed to such dimensions that gases may be readily 55 drawn therefrom laterally and I have found that a maximum path of substantially five inches to the nearest point of escape from the bed of fuel furnishes, so far as is now known to me, a proper dimensioning of parts. 60

Furthermore, to completely realize the conditions set out above the combustible gases which escape from the fuel must encounter a current of excess oxygen and be 65 intimately mixed therewith at a temperature sufficiently high to produce the combustion thereof, and this encounter and admixture should take place as quickly as possible after the liberation of the gases—when they are as nearly nascent as may be. In the two 70 structures which I have illustrated in the accompanying drawings as being adapted to carry out the process, these means are provided in slightly different manners. In the form shown in Figures 1, 2 and 3 there are 75 provided a series of small, vertically extending, combustion chambers formed in the fire pot walls, these chambers having restricted openings communicating with the fire pot throughout their height, being open at the 80 bottom for the entrance of an upwardly moving column of air and providing means at the top for the escape of their contained gases to the stack. In the furnace shown in Figs. 4 and 5 the fuel is contained in a 85 closed top fuel chamber open at its sides near the bottom; and at the sides of the fuel pot so constructed there are arranged a plurality of water tubes affording restricted 90 passages between them, said restricted passages constituting the combustion chamber of this type of boiler. The spaces between these tubes at the bottom afford openings for the admission of the upwardly passing current of air and the corresponding spaces at 95 the top allow the products of combustion to escape to a space above the closed top fuel chamber and ultimately to the stack.

In the two sheets of drawings accompanying this application and forming a part 100 hereof—

Fig. 1 is a central vertical section through one type of furnace and boiler adapted to carrying out my invention;

Fig. 2 is a horizontal section through the half of the furnace and boiler shown in Fig. 1 taken on the line 2—2 of that figure;

Fig. 3 is a vertical section on the line 3—3 of Fig. 2;

Fig. 4 is a transverse vertical section through a different design of furnace adapted to carrying out my process, the line on which this section is taken being indicated 10 by the line 4—4 of Fig. 5; and

Fig. 5 is a central, longitudinal, vertical section of the furnace shown in Fig. 4, taken on the line 5—5 of that figure.

Reference may now be had particularly to 15 these drawings, in order that the structures there illustrated as adapted to the carrying out of my invention may be thoroughly understood. In the furnace and boiler shown in Figs. 1, 2 and 3 let 6 represent a series of 20 intermediate transverse boiler sections interposed between front and rear sections 7 and 8, all of said sections being connected by upper and lower rods 9 and 10 which are secured in position by nuts 11 applied to 25 their exposed extremities. These sections are all hollow to contain the water to be heated, provision for the circulation of which is made in the manner customary in such constructions. The sections are further so constructed and arranged that a fire 30 pot 12 is formed in the lower part of the space inclosed by the several sections. The side walls of the sections, and the end walls as well if desired, throughout the chamber 35 formed between their vertical water legs, are provided with vertical combustion flues or chambers 13 which are in communication with the space inclosed by the sections throughout their lengths by restricted openings 40 14 as shown and which are open at their bottoms to the ash pit. Pivoted normally open dampers 15 (Fig. 3) form means for closing the bottoms of these combustion chambers when desired.

The bottom of the fire pot 12 is closed by 45 a grate 16 which may be of the customary shaking type as shown. The numeral 17 indicates the firing door, which it will be observed is high, and 18 indicates the stack to 50 which the products of combustion may escape from the top of the fuel chamber after having entered the same from the restricted combustion chambers 13 through the portions of the openings 14 above the fuel bed.

In Figs. 4 and 5 I have illustrated what 55 may be termed a water tube construction in which the cored out combustion chambers of the preceding construction are replaced by narrow spaces between the tubes. In this 60 setting there are provided a number of sections closely resembling the usual type of radiator sections, each having two legs with an open space between, the several sections being connected at the top and bottom for 65 the circulation of water and the several sec-

tions being spaced slightly one from the other as indicated in Fig. 5. The customary cold or return pipe 21 and steam or hot water pipe 22, leading if desired from a drum 23, are provided, these details of construction forming no part of the present invention.

The fuel chamber 24 is partially inclosed by a closed top and open bottomed casing 25 which stops as indicated some little distance above the grate 26, thus necessitating that the distillates and products of combustion in escaping from the bed of fuel must proceed laterally and pass through the spaces between the sections 20 before finding their way to the stack 27. A chamber 28 above the top of the casing 25 forms a means of collecting the products of combustion after they have passed up between the sections 20 and conducting them to the stack 27 at the rear of the boiler. Such a boiler furnace is also preferably provided with an upper feed door 29 and a lower feed door 30 so constructed with engaging flanges that the lower door may not be opened except when the upper one has been opened. This prevents the lower door only being opened which is desirable as in the ordinary running of the furnace after starting the bed of fuel always extends thereabove. The door 30 therefore is usually closed except when laying a new fire. A closed casing 31 resting on the base 32 serves to retain the products of combustion from lateral escape after their passage into the spaces between the boiler sections.

Operation.

Referring first to the type of furnace and boiler shown in Figs. 1, 2, and 3, in starting the furnace a comparatively thin fire may first be laid on the grate and at this time the dampers 15 are preferably closed to increase the draft through the fire, which, until thoroughly started, burns in the ordinary manner with the products of combustion passing upwardly therethrough. After a good fire is started much more fuel is thrown on so that the bed of fuel is practically impervious to the gases generated and the dampers 15 are opened to allow the draft to draw upwardly through the combustion chambers or flues 13 a supply of air which is heated as it rises. The hydrocarbons which distil from the raw fuel when it reaches a certain temperature and any carbon monoxide resulting from incomplete combustion are drawn laterally through the bed of fuel to the most available combustion chamber 13 and there they meet a rising sheet of flame from the combustion of the fixed carbon in the lower portion of the bed of fuel mixed with an excess of oxygen supplied by the air drawn into the combustion chambers from the ash pit. The areas of the chambers being relatively small and the current of rising flame

and oxygen which the gases meet being at substantially right angles to their path as they are drawn from the fuel bed, intimate admixture of the combustible gases with the 5 flames and the oxygen carrying heated air takes place. The flames from the fixed carbon highly heat the mixture and the gases meet the oxygen so soon after their liberation as to be substantially in a nascent state; 10 complete and smokeless combustion of these portions of the fuel consequently ensues.

A marked advantage of my process further arises from the fact that the distillation of the gaseous constituents of the fuel is slow, 15 gradual and continuous instead of being sudden and intermittent as is always the case when fresh fuel is thrown on a glowing fire. There is therefore ample opportunity for the flames which result from the subsequent 20 combustion of the fixed carbon in the active combustion zone mixing with and burning the gaseous constituents constantly being distilled off in a higher zone, and the temperature of that part of the fire which is 25 consuming the fixed carbon is not lowered as is the case where raw fuel is thrown on a glowing fire.

In the use of the apparatus shown in Figs. 4 and 5 substantially the same operation 30 is carried out. This apparatus, however, draws the distillates and other combustible gases from the fuel only below a certain line (the lower edge of the casing 25) and therefore if distillation takes place 35 above that line the gases must travel down to escape into the combustion chambers constituted by the passages between the water tubes. For this reason a fire in this apparatus may require a little more frequent attention 40 to maintain the proper working conditions than obtains with the other apparatus. But coal of higher quality may be employed as imperviousness of the bed of fuel itself is not requisite since the casing 25 beginning closed at the top will effectually prevent any upward escape of gases. In this construction the interstices between the several boiler sections are so small as to prevent the fuel falling from its chamber thereinto and 45 as to result in the intimate admixture between the combustible gases and distillates and the excess oxygen carrying flame requisite to the proper carrying out of my process.

The combustible products arising from a 50 bed of fuel during combustion comprise distilled hydrocarbons, uncombined carbon, hydrogen from dissociated water vapor, and partially combined carbon (CO) and in the claims I have employed the term combustible 55 gaseous products to indicate any or all of the products named.

In the apparatus disclosed for carrying out my process there are shown no means for withdrawing the combustible gaseous 60 products from the ends of the fuel bed

though it will be evident that such means may be utilized if desired. The expression "laterally" employed in the claims as defining the direction in which the gases are withdrawn should therefore be interpreted 70 to include endwise as well as side wise.

Having thus described my invention, what I claim and desire to secure by Letters Patent is:—

1. The herein described process of promoting combustion which comprises maintaining a relatively deep and narrow bed of solid carbonaceous fuel, withdrawing the combustible gaseous products from the fuel laterally and gradually and discharging 75 them directly into a rising column of flame carrying an excess of oxygen, said flame being that resultant from the combustion of the fixed carbon of the fuel, and the fuel bed being so proportioned that said combustible 80 gaseous products are not required to travel more than about five inches through the fuel before being discharged into the rising flame column.

2. The herein described process of promoting combustion which comprises maintaining a relatively deep and narrow bed of solid carbonaceous fuel with only the lower portion thereof in a state of ignition, withdrawing the combustible gaseous products 95 from the fuel laterally, gradually and directly into a rising column of flame carrying an excess of oxygen, said flame being that resultant from the combustion of the fixed carbon of the fuel.

3. The herein described process of promoting combustion which comprises maintaining a relatively deep and narrow bed of solid carbonaceous fuel with only the lower portion thereof in a state of ignition, preventing 100 the escape of the combustible gaseous products upwardly through said fuel, withdrawing said combustible gaseous products from the fuel laterally, gradually and directly into a rising column of flame carrying an 105 excess of oxygen, said flame being that resultant from the combustion of the fixed carbon of the fuel.

4. The herein described process of promoting combustion which comprises maintaining a relatively deep and narrow bed of solid carbonaceous fuel with only the lower portion thereof in a state of ignition, the depth and nature of said fuel bed being such as to prevent the passage of gases upwardly 110 therethrough, withdrawing the combustible gaseous products from the fuel laterally, gradually and directly into a rising column of flame carrying an excess of oxygen, said flame being that resultant from the combustion 115 of the fixed carbon of the fuel.

5. The process of promoting combustion which comprises maintaining active combustion in a lower zone of a substantially vertical column of solid carbonaceous fuel while 120

substantially preventing escape of gases from the upper end of said column, supplying an excess of oxygen to the flames issuing laterally from the zone of active combustion of 5 said solid fuel, and guiding the mixture upwardly and into contact with combustible gases issuing laterally from the fuel column above the zone of active combustion.

6. The process of promoting combustion 10 which comprises maintaining active combustion in only the lower portion of a relatively deep and narrow column of solid carbonaceous fuel while substantially preventing escape of gases from the upper end of said column, supplying an excess of oxygen to the flames issuing laterally from the region of active combustion of said solid fuel and guiding the mixture upwardly and into contact with combustible gases issuing laterally 15

from the fuel column above the region of active combustion. 20

7. The process of promoting combustion which comprises maintaining active combustion at one end portion only of a column of solid carbonaceous fuel while substantially preventing escape of gases from the other end of said column, supplying an excess of oxygen to the flames issuing laterally from the region of active combustion of said 25 solid fuel, and guiding the mixture along the outside of said column and into contact with combustible gases issuing laterally from an intermediate portion of said column. 30

In testimony whereof I have hereunto aff- 35 fixed my signature.

EDWIN C. LILLIE.
